UNITED STATES PATENT OFFICE

2,646,051

COMBINED SMOKING DEVICE AND
FLASHLIGHT

George Lyeso, Wendel, W. Va.

Application May 28, 1951, Serial No. 228,607

4 Claims. (Cl. 131—178)

1

This invention relates to a combined flashlight and smoking device (pipe, or cigarette or cigar holder) of the general type disclosed in my expired U. S. Patent 1,951,097 of March 18, 1934.

One object of the present invention is to provide a greatly simplified construction which may be constructed more easily and at less cost, may be easily repaired if necessary, will preserve advantages of the prior structure, and will possess other advantages not present in said prior structure.

In carrying out the above end, another object is to provide a novel construction in which the smoke conducting ports and tube are free from abrupt angles and may therefore be easily cleaned with an ordinary pipe cleaner.

Yet another object is to provide a novel construction for normally connecting the mouthpiece with the body of the smoking device, allowing easy separation of these parts, and exposing all smoke passages for substantially straight-line cleaning when said parts are separated.

The connecting means between the body and the mouthpiece includes a ferrule attached to the mouthpiece and rearwardly slidable from the body when said mouthpiece is rearwardly pulled; and an additional object is to provide a novel construction in which a single central fastener extends through a rear end wall of said ferrule and secures the latter to the mouthpiece, and in which a smoke tube secured in the ferrule has a rear end which extends into the mouthpiece in laterally spaced relation with said fastener; whereby the ferrule and mouthpiece are held against relative rotation.

A further object is to provide a novel construction in which the front portion of the smoke tube is slidably received in the rear portion only of the smoke port of the body and is rearwardly slidable therefrom when the mouthpiece and ferrule are unitarily pulled rearwardly from the body.

A still further object of the invention is to provide the ferrule with an internal spring which exerts a forward force on the flashlight battery to hold the usual central contact of the latter against the usual central contact of the light bulb.

Yet another object is to utilize the aforesaid central fastener of the ferrule to mount the spring which forces the battery forwardly.

A still further object is to provide a novel switch construction whereby the flashlight may be turned on and off by movement of a push button, instead of requiring rotation of the lens and reflector carrier as in the prior construction.

2

Yet a still further object of the invention is to provide a novel construction in which the flashlight circuit is independent of the smoke tube.

The above mentioned objects have been attained by the improved construction shown in the accompanying drawing, in which

Figure 1 is a side elevation of a combined pipe and flashlight constructed in accordance with the invention,

Figure 2 is an enlarged central vertical longitudinal sectional view,

Figure 3 is an enlarged horizontal sectional view on line 3—3 of Figure 1,

Figures 4 and 5 are transverse sectional views on lines 4—4 and 5—5 of Figure 2, and

Figure 6 is a side elevation, partly in section, showing a cigarette holder constructed in accordance with the invention.

The drawing illustrates the preferred construction and while this construction will be rather specifically described, it is to be understood that variations may be made within the scope of the invention as claimed.

In the construction shown in Figures 1 to 5, a horizontally elongated stem 10 is provided at its front end with a bowl 11, said stem and bowl being preferably formed from briar or other wood. The rear end 12 of the stem 10 is slightly reduced in diameter and is slightly tapered. The upper portion of this tapered end is formed with a longitudinal slot 13, and a smoke port 14 in the upper portion of the stem 10 extends from the bowl 11 to the front end of said slot 13, the rear end of said port being slightly enlarged.

A suitable mouthpiece 16 is provided, said mouthpiece having a smoke port 17 free from any abrupt angles. The front end 18 of this port is near the upper side of the mouthpiece 16 and is slightly enlarged. This enlarged port end 18 opens through the front end surface 19 of the mouthpiece 16.

A tapered ferrule 20 is provided at the front end of the mouthpiece 16, said ferrule having an integral rear end wall 21 which abuts the end surface 19 of said mouthpiece. A single central screw 22 extends through the end wall 21 and into the mouthpiece 16 to unitarily secure the mouthpiece 16 and the ferrule 20 together. This ferrule snugly yet slidably surrounds the reduced rear end 12 of the stem 10 and provides an air-tight connection.

A rigid smoke tube 23 extends longitudinally through the upper portion of the ferrule 20 and is soldered or otherwise rigidly secured to the peripheral wall of said ferrule. The front portion 24 of this smoke tube 23 is slidably received

in the enlarged rear end 15 of the smoke bore 14 to rearwardly withdraw therefrom when the mouthpiece 16 and ferrule 20 are rearwardly pulled from the stem 10. The portion of the tube 23 immediately behind the projecting end 24 is received in the slot 13 of the stem 10. The rear end portion 25 of this tube is received in the enlarged front end 18 of the mouthpiece port 17. Thus, the tube 23 holds the ferrule 20 and stem 10 against relative rotation, and it also holds said ferrule and the mouthpiece 16 against relative turning about the screw 22.

When the smoke ports 14 and 17, and the smoke tube 23 need cleaning, this may be done with an ordinary pipe cleaner, either with or without removing the mouthpiece 16 and its ferrule 20 from the stem 10, as said ports and tube have no abrupt turns to interfere with passage of the cleaner therethrough.

Should a new mouthpiece be required at any time, the screw 22 will permit easy detachment of the old and substitution of the new.

All required components of a flashlight are embodied in the structure. To accommodate them, the stem 10 is formed with a longitudinal bore 26 which is open at both ends of said stem. At one side of this bore 26 a short longitudinal slot 27 extends from said bore to the exterior of the stem 10.

An assembly of bulb 28, reflector 29, lens 30, and carrier ring 31 is provided at the front end of the bore 26, said carrier ring 31 being threaded into said front end of said bore. The bulb 28 has the usual central contact 32 and metal shell 33, and this shell is threaded through a sleeve 34 on the metal reflector 29.

A battery 35 is snugly yet removably received in the bore 26 and includes the usual metal shell 36 and central contact 37. This contact 37 abuts the bulb contact 32. To maintain the proper contact engagement, a spring 38 is provided, exerting a forward force on the battery 35, said spring being mounted by means of the above-described screw 22 and being preferably of coiled form.

An elongated switch-forming conductor strip 39 is longitudinally positioned at the slotted side of the bore 26 and contacts slidably with the wall of said bore and with the battery shell 36. This strip 39 is provided with a flat-sided neck 40 extending through the slot 27, the outer end of said neck having a push button 41. When this push button occupies its rearmost position, the strip 39 is out of contact with the reflector 29, but when said button is pushed forwardly, the strip 39 contacts with said reflector and the flashlight circuit is thus closed. The flat-sided neck 40, by contact with the side walls of the slot 27, holds the strip 39 against canting from its proper longitudinal position in the bore 26.

In Figure 6, a combined flashlight and cigarette holder is shown. The construction of this article substantially duplicates that above described, but a cigarette socket 44 is provided instead of a bowl. Only a few of the elements are shown in this view and they bear the same reference numerals used in the above description, plus the exponent a.

From the foregoing, it will be seen that novel and advantageous structure has been provided for attaining the desired ends, and while preferences have been disclosed, attention is again invited to the possibility of making variations

therein without departing from the spirit and scope of the invention as claimed.

I claim:

1. In a smoking device of the character described an elongated stem having a smoke port adjacent the upper side which opens through its rear end, with an enlarged chamber at its lower side; a mouthpiece having a smoke port, the front end of this smoke port being within the upper portion of said mouthpiece, a ferrule secured to the front end of said mouthpiece and slidably surrounding the rear end of said stem to slide from the latter when said mouthpiece is rearwardly pulled, a rigid smoke tube secured in the upper portion of said ferrule and in obtuse angle communication with said smoke port of said mouthpiece and acting to prevent relative rotation of the stem and mouthpiece, the front end portion only of said smoke tube being slidably received in the rear end portion of said smoke port of said stem to withdraw therefrom when said mouthpiece and ferrule are unitarily pulled rearwardly, said smoke tube having such an angle as to allow easy passage of a pipe cleaner through said tube and said smoke ports.

2. A structure as specified in claim 1; said stem having a longitudinal recess opening through its periphery with its rear end in alignment with the smoke port of said stem; said smoke tube being secured against the peripheral wall of said ferrule and having a relatively short front end portion projecting forwardly beyond said ferrule into said smoke port of said stem, the ferrule-contained portion of said smoke tube being received in said longitudinal recess.

3. A structure as specified in claim 1, said ferrule having a rear end wall, and a substantially central fastener extending through said end wall into said mouthpiece and securing said ferrule and mouthpiece together, said smoke tube having a rear end portion projecting beyond said end wall into said mouthpiece laterally of the central fastener and thereby holding said ferrule and mouthpiece against relative turning about said fastener.

4. A structure as specified in claim 1; said stem having a longitudinal recess opening through its periphery with its rear end in alignment with the smoke port of said stem; said smoke tube being secured against the peripheral wall of said ferrule and having a relatively short front end portion projecting forwardly beyond said ferrule into said smoke port of said stem, the ferrule-contained portion of said smoke tube being received in said longitudinal recess; said ferrule having a rear end wall, and a substantially central fastener extending through said end wall into said mouthpiece and securing said ferrule and mouthpiece together, said smoke tube having a rear end portion projecting beyond said end wall into said mouthpiece laterally of the central fastener and thereby holding said ferrule and mouthpiece against relative turning about said fastener.

GEORGE LYESO.
